UNITED STATES PATENT OFFICE

CHARLE LECHNER, OF FRANKLIN, LOUISIANA, ASSIGNEE OF ONE-HALF TO FRITZ SCHOENSTEIN, OF FRANKLIN, LOUISIANA.

NAIL AND SPIKE EXTRACTOR.

1,167,574.

Specification of Letters Patent.

Patented Jan. 11, 1916.

Application filed June 5, 1914. Serial No. 843,874.

To all whom it may concern:

Be it known that I, CHARLE LECHNER, a citizen of the United States, residing at Franklin, in the parish of St. Mary and State of Louisiana, have invented a new and useful Nail and Spike Extractor, of which the following is a specification.

This invention relates to a tool and more particularly to one designed for the extraction of nails, spikes and allied articles, and aims to provide a novel device of that character having powerful and effective means to accomplish the ends desired.

In the drawings accompanying this specification and forming a part thereof, the preferred embodiment of my invention has been shown, in which:—

Figure 1 is a view in perspective of my improved nail and spike extractor. Fig. 2 is a fragmental view illustrating in section the base and contiguous parts.

Referring to the drawings in which similar reference numerals designate corresponding parts throughout the several views, a base 3 is provided at its rear extremity with the upstanding ears 4 and with a second pair of ears 5 spaced there in front.

The forward or front extremity of the base is beveled so as to form the wedge-shaped end 6 into which extends the rearwardly projecting slot 7 for the reception of the shank of a nail or spike during the process of the nail or spike extraction.

The movable jaw 8 is wedge-shaped at its forward extremity and is provided with the nail engaging slot 9 extending therein which lies directly above the slot 7 of the stationary jaw or wedge-shaped end 6 of the base. The movable jaw is angular or L-shaped and is pivoted at its elbow to the spaced ears 5 through the intervention, or by means, of the pivot pin 10.

An actuating lever 12 is rotatably secured to the ears 4 by the pivot pin 13, it being thus mounted for limited oscillatory motion, which motion will produce or accomplish the extraction of the nail which is at that time in engagement with the nail receiving slot 9. The lever 12 is provided with a plurality of apertures 14 to which is adjustably secured the links 15. The links are mounted for adjustable and pivotal engagement with the lever 12 while the opposite extremities are pivotally secured to the upstanding arm 11 of the movable jaw.

The actuating lever 12 is provided at its upper extremity with the socket 17 in which is removably mounted the handle 18, it being noted, however, that the socket is for the sake of convenience only and the invention includes other details for the accomplishment of the same purpose.

The base 3 is bifurcated as at 19 for the rotatable mounting of the movable jaw 8 and lever 12. The base is provided at its rear extremity with the serrated under surface 20 which lies directly beneath the lever 12, and thus prevents the slipping or accidental displacement of the tool when pressure is brought to bear upon the handle, such as is necessary for the extraction of a nail or spike or other use of the implement.

Among the many and desirable features of the present device, particular mention is made of and stress laid upon the wedged manner in which the front extremity 6 and movable jaw are formed. The formation in question allows the device to be used as a wedge for the prying apart of two objects. An actuation of the handle will then result in the further separation of the two articles, which thus takes the place of a crow-bar or allied tool when either limited space or other reasons negotiate the use of the latter. The linked and adjustable manner in which the movable jaw is connected to the lever 12, provides for the variation of the lever ratio between the movements of the movable jaw and the actuating handle. Thus should a long stroke be desired, the link is shifted away from the fulcrum of the actuating lever which accomplishes the desired result. However, should it be desired to shorten the stroke of the movable jaw or to increase the force or turning moment of the same with the application of equal forces upon the handle, the same may be accomplished with facility by lowering the links *i. e.* bringing the one extremity thereof closer to the fulcrum or pivot pin 13 of the lever.

Having thus fully described my invention and referred specifically to several of the advantages thereof, what I desire to procure by Letters Patent and claim is:

An extractor embodying an elongated shoe having a wedge-shaped claw at its forward end and flush with its lower surface, an open slot extending from the rear end of the shoe to the butt end of said claw, a pair of upstanding ears at the rear end of the

shoe at the opposite sides of said slot, and a pair of upstanding ears at the opposite sides of said slot adjacent the butt end of said claw, said claw having an open U-shaped slot extending from its sharp end, an angular lever having its elbow fulcrumed between the second mentioned pair of ears and working in the first mentioned slot, one arm of said lever being in the form of a wedge-shaped claw adapted to swing snugly upon the first mentioned claw and having an open V-shaped slot above said U-shaped slot of the first mentioned claw, the other arm of said lever projecting upwardly, a power lever having its lower end fulcrumed be-

tween the first mentioned pair of ears and working in the first mentioned slot, and a link connecting the upwardly projecting arm of the angular lever with the power lever, the lower surface of the shoe being 20 toothed at opposite sides of the first mentioned slot adjacent the rear end of the shoe.

In testimony that I claim the foregoing as my own, I have hereto affixed my signature in the presence of two witnesses.

CHARLE LECHNER.
